L. L. MILLER

ALMOND HULLER

Filed Nov. 11, 1922

INVENTOR.
L.L. Miller
BY *George Webster*
ATTORNEY

UNITED STATES PATENT OFFICE.

LAURENCE L. MILLER, OF RIPON, CALIFORNIA.

ALMOND HULLER.

Application filed November 11, 1922. Serial No. 600,415.

To all whom it may concern:

Be it known that I, LAURENCE L. MILLER, a citizen of the United States, residing at Ripon, county of San Joaquin, State of California, have invented certain new and useful Improvements in an Almond Huller; and I do declare the following to be a full, clear, and exact description of the same, reference being had to the accompanying drawings, and to the characters of reference marked thereon, which form a part of this application.

This invention relates to improvements in almond-hulling machines, the principal objects in view being to provide a huller in which the nuts will be efficiently hulled and the danger of cracking the shells while so doing reduced to a minimum; one from which the hulled nuts and the hulls will drop easily and without any danger of their sticking between the grate bars; and one so constructed that adjustments to suit different conditions as to the kind and size of the nuts to be hulled may be very quickly and easily made.

A further object of the invention is to produce a simple and inexpensive device and yet one which will be exceedingly effective for the purposes for which it is designed.

These objects I accomplish by means of such structure and relative arrangement of parts as will fully appear by a perusal of the following specification and claims.

In the drawings similar characters of reference indicate corresponding parts in the several views.

Fig. 1 is a longitudinal section of the huller.

Fig. 2 is a cross section thereof.

Fig. 3 is a fragmentary perspective of a grate-bar unit, detached.

Referring now more particularly to the characters of reference on the drawings, the numeral 1 denotes a pair of substantially horizontal parallel beams, suitably spaced apart and connected by cross beams 2, making a rigid rectangular frame. This frame is pivotally supported from the floor at one end on a transverse shaft 3 which is journaled in uprights 4 mounted on the floor and extending upwardly alongside the frame. The opposite end of the frame is supported by a chain or cable 5, the upper end of which is wound about a drum 6 on a shaft 7 suitably supported above the frame, or the chain may be wound directly

about the shaft itself. It will thus be seen that by turning said shaft 7, the chain will be raised or lowered, thereby altering the angle of setting of the frame relative to the floor.

Journaled in the cross beams 2 and extending lengthwise of the beams 1 and centrally therebetween is a shaft structure 8 in axial alinement with the shaft 3 and driven therefrom by means of bevel gearing 9. The shaft 3 itself is driven by any suitable power through a belt 10 running over a pulley 11 on said shaft, or by any other suitable means, as may be desired.

Situated between the beams 1 and substantially concentric with the shaft 8 is a circular drum 12, preferably made of sheet metal, a portion of said drum to the extent of about 90° of its periphery being cut away lengthwise from a point substantially at the bottom of the drum upwardly around that side in the direction of rotation of the shaft 8. Reinforcing bars 13, projecting outwardly, extend along the edges of the open area.

Adapted to removably fit into the cut-away or open area are grate bar units 14 and 15 of equal length, so as to be interchanged with each other if desirable. Each unit comprises a plurality of peripherally disposed and circular rods or bars 16 suitably spaced apart lengthwise of the drum; those of the unit 14 being spaced closer together than those of the unit 15.

Connecting each set of rods together outwardly of or under the same, are bars 17 and 18.

The bars 17 are at the lower ends of the rods and are flush with said ends, being adapted to lie against that side of the adjacent angle bar 13 which faces the cut-away portion of the drum, the inner or upper edges of the rods 14 and 15 at that end being in alinement with the inner surface of the drum, and forming a continuation of the curvature thereof.

The opposite ends of said rods extend somewhat beyond the bars 18, so as to overlap and rest on the adjacent drum surface, said bars 18 lying against that side of the adjacent angle bar 13 which faces inwardly of the open area of the drum.

Removable bolts 19 hold the members 17 to the adjacent bar 13, but no holding means for the bars 18 is necessary other than that provided by the overlap of the grate bars

on the drum surface. This last named feature is also an aid in preventing possible cracking of the nut-shells, since there is a drop between the inner edge of the grate rods and the drum surface rather than an obstructing wall or edge, the nuts tending to be forced from the former onto the latter.

At the lower ends of the grates, however, the reverse conditions obtain, the nuts moving from the drum on to the grate.

Separate discharge chutes 20 lead from under the grates, so that the discharge from each grate may be segregated and given different treatment should it be necessary.

15 The reason for making the grate units with different spacing between the bars but of the same overall length is because I have found from experience that when handling different kinds of nuts, better results may be obtained by altering the spacing of the grates, the grate unit used with one kind of nut at the intake end being sometimes removed from said end and placed at the lower end of the drum for a different kind 20 of nut, another grate unit, with still closer bars being then mounted at the intake end.

25 Or the lower-end grating may be placed at the intake end, and another grate with still wider spaced bars mounted in the lower 30 end.

A chute or hopper 21 leads to the intake or high end of the drum.

Mounted on the shaft 8 over that portion thereof within the drum are suitably spaced 35 and radially disposed rods 22, disposed in staggered order, and serving as beaters to strike the nuts as they enter and travel through the drum.

40 The drum is adjustably supported from the beams 1 for vertical movement relative thereto by means of brackets 23 at both ends of the drum and overhanging the beams.

45 Adjustable bolts 24, mounted in the beams, bear against the under side of the brackets, so that by raising and lowering said bolts the drum may be raised or lowered at each end individually, or at both ends together.

50 At the same time, the drum is firmly held in any desired position by bolts 25 passing through lateral slots 23^a in the brackets and into said beams, which allows of lateral adjustment of the drum relative to the shaft.

55 In this manner, the spacing of the beater rods from the grates may be adjusted both vertically and laterally to suit different conditions of operation, since the spacing of said rods from the top portion of the drum 60 is a matter of no importance.

Also, the spacing of the beaters from the grates may be made different at opposite ends of the drum, depending on conditions and the judgment of the operator.

65 As previously described, the angle of the

structure as a whole, without disturbing said drum adjustment, may be altered by manipulation of the chain 5.

By the use of the peripherally rather than longitudinally disposed grate bars as usual, I am enabled, without weakening the structure, to use shallower bars than is possible with the last named arrangement, as they are more self supporting, and there is thus but a very small distance for the nuts to fall before they are entirely clear of the grates, thus avoiding the chance of the hulls or nuts wedging between the bars, as frequently happens with the ordinary form of construction.

Also I have found that round rather than square bars aid materially in this quick-discharge action, since the tendency of the nuts and hulls is to roll through easily, there being no sharp edges to hinder their passage.

From the foregoing description it will be readily seen that I have produced such a device as substantially fulfills the objects of the invention as set forth herein.

While this specification sets forth in detail the present and preferred construction of the device, still in practice such deviations from such detail may be resorted to as do not form a departure from the spirit of the invention, as defined by the appended claims.

Having thus described my invention, what I claim as new and useful and desire to secure by Letters Patent is:

1. An almond huller comprising a drum, a shaft projecting therethrough and having beater members thereon, means for adjusting the angle of setting of the drum and shaft as a unit, and independent means for adjusting the concentric setting of the drum relative to the shaft.

2. An almond huller comprising a drum, a shaft projecting therethrough and having beater members thereon, means for adjusting the angle of setting of the drum and shaft as a unit and independent means at both ends of the drum for enabling the concentricity of the latter relative to the shaft to be adjusted independently at either end of said drum.

3. An almond huller including a drum cut away lengthwise for a portion of its extent, and grate bars extending over the cut-away area peripherally of the drum; the inner edges of the bars at one end lying flush with the inner edge of the drum and the opposite ends of said bars having open spaces therebetween and overlapping the inner face of the drum adjacent the cut-away area thereof.

4. An almond huller including a drum cut away lengthwise for a portion of its extent, re-inforcing bars extending along the longitudinal edges of the drum surrounding the cut away area, and outwardly thereof, grate bars extending peripherally of the

drum over said area and bars extending outwardly of the grate bars and lengthwise of the drum and to which said grate bars are connected, said other bars being adapted to fit between said re-inforcing bars.

5. An almond huller including a drum cut away lengthwise for a portion of its extent, re-inforcing bars extending along the longitudinal edges of the drum surrounding the cut away area, and outwardly thereof grate bars extending peripherally of the drum over said area and bars extending outwardly of the grate bars and lengthwise of the drum and to which said grate bars are connected, said other bars being adapted to fit between said re-inforcing bars, and means removably holding said last named sets of bars to each other.

6. An almond huller including a drum cut away lengthwise for a portion of its extent, reinforcing bars extending along the longitudinal edges of the drum surrounding the cut away area, and outwardly thereof grate bars extending peripherally of the

drum over said area and bars extending outwardly of the grate bars and lengthwise of the drum and to which said grate bars are connected, the grate bars at one end extending beyond the adjacent longitudinal bar whereby to rest on the adjacent inner face of the drum while said longitudinal bar lies against the adjacent reinforcing bar; the opposite ends of the grate bars lying flush with their adjacent longitudinal bar while the latter lies against the corresponding reinforcing bar, and removable bolts holding said last named bars in place.

7. An almond huller including an inclined frame pivoted at one end, vertically adjustable means supporting the other end, a shaft journaled lengthwise in the frame, a drum surrounding the shaft, brackets on the drum at the ends thereof overhanging the frame, and vertically adjustable bolts in the frame, the brackets resting on said bolts.

In testimony whereof I affix my signature.
LAURENCE L. MILLER.
